and his successors in office

No Drawing. Application October 27, 1943,
Serial No. 507,892

4 Claims. (Cl. 260—236)

(Granted under the act of March 3, 1883, as
amended April 30, 1928; 370 O. G. 757)

This application is made under the act of March 3, 1883, as amended by the act of April 30, 1928, and the invention herein described, if patented, may be manufactured and used by or for the Government of the United States of America for governmental purposes without the payment to us of any royalty thereon.

Our invention relates to the preparation of myosmine. Myosmine has been previously isolated in minute quantities from tobacco smoke. Subsequent study of the alkaloid obtained from this source led to a determination of the approximate structural formula of myosmine. The exact chemical structure was later postulated on the basis of a synthetic procedure in which ethyl nicotinate was condensed with N-benzoyl pyrrolidine and the resulting product converted to myosmine by hydrolysis with fuming hydrochloric acid under pressure.

We have found that myosmine can be prepared by the pyrolysis of nicotine at temperatures substantially above the normal boiling point of the nicotine. This novel procedure facilitates the preparation of myosmine in quantities heretofore unattainable since it is readily adaptable to large scale production. In view of the fact that this alkaloid is reported to be responsible, wholly or in part, for the aroma of tobacco smoke, it is possible that myosmine may prove a valuable adjunct to tobacco. In a copending application filed concurrently herewith, we have shown that small quantities of this alkaloid impart a characteristic aromatic flavor to tobacco and tobacco smoke.

In our process myosmine is obtained by passing nicotine over siliceous materials, such as silica gel or fused quartz, at temperatures above 450° C. The best yields of the desired product were obtained at about 570° C. but pyrolyses conducted throughout the temperature range of 500 to 650° C. have produced myosmine. Space velocity variations between 136 and 332 have been successfully employed. The term "space velocity," as used herein, means the cc. of nicotine per hour at reaction temperature per cc. of contact material. Both Pyrex and iron have been found to be suitable reactor materials.

Myosmine was isolated from the pyrolysis products by distillation at sub-atmospheric pressures through an efficient fractionating column. The

following table includes the boiling points of myosmine fractions collected at various reduced pressures:

	B. P. range, °C.	Pressure, mm.
8	86.0-89.0	0.3
9	99.5-104.0	1.0
10	101.5-107.0	1.3
11	115.0-120.0	3.4
12	119.0-128.2	4.4
13	124.0-130.0	8.0

The above fractions readily solidified on cooling to about 5° C. and could be further purified by washing with chilled petroleum ether. A sample of myosmine subjected to this procedure melted at 44.0 to 45.0° C., which agrees with the reported melting point. The carbon, hydrogen, and nitrogen analytical values of this purified product were in accord with the theoretical composition $C_8H_{10}N_2$. The picric acid derivative of the alkaloid melted at 184.0 to 185.0° C., which is the reported melting of myosmine picrate.

The following examples illustrate our invention:

Example I

220 grams of nicotine were passed over 124 cc. of 4-mesh quartz chips in an iron reactor at a uniform rate over a period of 325 minutes. The reactor consisted of an iron pipe of 1 inch internal diameter which was supported in a vertical, tubular, electrically heated furnace. The temperature of the quartz chips was maintained at about 550° C. throughout the experiment. The pyrolysis products were collected in a receiving train consisting in turn of an ice-cooled flask, a water-cooled condenser, and a Dry-Ice trap.

Distillation of the condensate through an efficient fractionating column yielded a fraction boiling at 115.0 to 120° C. at 3.4 mm. which solidified on cooling to 5° C. The picric acid derivative of this material melted at about 184.0 to 185.0° C. which is the melting point of myosmine picrate. A sample of the white solid obtained by cooling the distilled fraction was washed with chilled petroleum ether and dried on a porous plate. The product melted at 44.0 to 45.0° C. which is the reported melting point of myosmine. Analysis: calculated for $C_8H_{10}N_2$: C=73.97%,

H=6.85%, N=19.18%. Found: C=73.74%, H=6.87%, N=19.38%. The identity of the myosmine was thereby confirmed.

Example II

218 grams of nicotine were passed over 124 cc. of 4-mesh quartz chips in the iron reactor described in Example I. The addition was made at a uniform rate over a period of 190 minutes and the reaction temperature was maintained at about 650° C. Myosmine was isolated from the pyrolysis products according to the procedure disclosed in Example I. A picric acid derivative of the myosmine fraction caused no melting point depression when mixed with the picric acid derivative obtained in the above example.

Example III

The apparatus and volume of quartz contact material were identical with that employed in Example I. 214 grams of nicotine were passed through the reactor at a uniform rate over a period of 190 minutes at a temperature of 570° C. Myosmine was isolated from the pyrolysis products according to the procedure disclosed in Example I. The picric acid derivative of the myosmine was shown to be identical with that obtained in Example I by the method of mixed melting points.

Example IV

201 grams of nicotine were passed over 168 cc. of 4-mesh quartz in a Pyrex reactor at a uniform rate over a period of 220 minutes. The reactor, which consisted of a Pyrex tube having an internal diameter of 1 inch, was supported in a vertical, tubular, electrically heated furnace. The

temperature of the contact material in this experiment varied from 585 to 620° C. Myosmine was isolated and identified according to the procedure described in Example II.

Example V

The quartz contact material employed in Example IV was replaced by an equal volume of 4 to 6 mesh silica gel. 200 grams of nicotine were passed through the reactor at a uniform rate over a period of 200 minutes. The reaction temperature was 500° C. Myosmine was isolated and identified in the reaction products according to the procedure disclosed in Example II.

Having thus described our invention, we claim:

1. The process of preparing myosmine which comprises pyrolyzing substantially pure nicotine in the presence of quartz at a temperature of about 500 to 650° C.
2. The process of preparing myosmine which comprises pyrolyzing substantially pure nicotine in the presence of quartz at a temperature of about 570° C.
3. The process of preparing myosmine which comprises pyrolyzing substantially pure nicotine in the presence of silica gel at a temperature of about 500° C.
4. In a process of preparing myosmine the step comprising pyrolyzing substantially pure nicotine in the presence of a contact material of the group consisting of quartz and silica gel at a temperature of about 500° to 650° C.
